UNITED STATES PATENT OFFICE.

JACOB JACOBS, OF BROOKLYN, NEW YORK.

DESIGN FOR A LENS.

SPECIFICATION forming part of Design No. 27,703, dated September 28, 1897.

Application filed May 8, 1897. Serial No. 635,752. Term of patent 14 years.

To all whom it may concern:

Be it known that I, JACOB JACOBS, of Brooklyn, in the county of Kings, and in the State of New York, have invented a certain new and original Design for Lenses for Illuminating-Gratings; and I do hereby declare that the following is a full, clear, and exact description thereof, reference being had to the accompanying drawings, in which—

10 Figure 1 is a perspective view of a lens embodying my design, and Fig. 2 is a cross-section of the same.

Letters of like name and kind refer to like parts in each of the figures.

15 The object of my invention is to provide a design for lenses for illuminating-gratings; and to this end said invention consists in the design for a lens, substantially as hereinafter specified.

20 The leading feature of my design consists of the lens A, provided with prisms B and B, having waved or scalloped edges b and b.

As shown in the drawings, the lens consists

of a plate A, having one face plane and on its other face a number of parallel ribs or 25 prisms B and B, that are triangular in cross-section, one face of each rib being perpendicular to the plate and the other inclined. The latter is a plane surface, but the perpendicular face has a waved or scalloped formation from end to end that is produced by a series of concavities b and b. 30

My lens has not only a unique appearance, but it has superior light-transmitting capacity.

Having thus described my invention, what I claim is—

The design for a lens, substantially as set forth.

In testimony that I claim the foregoing I 40 have hereunto set my hand this 7th day of May, 1897.

JACOB JACOBS.
